REFRIGERATING APPARATUS

Charles F. Kettering, Dayton, Ohio, assignor to
General Motors Corporation, Dayton, Ohio, a
corporation of Delaware

Application December 24, 1934, Serial No. 758,882

15 Claims. (Cl. 62—6)

This invention relates to air conditioning.

It is an object of this invention to provide an air conditioner in which the absolute humidity of the air may be reduced either without materially varying the dry bulb temperature or with the lowering of the dry bulb temperature in varying degrees.

Further objects and advantages of the present invention will be apparent from the following description, reference being had to the accompanying drawing, wherein a preferred form of the present invention is clearly shown.

In the drawing:

Fig. 1 is a view, somewhat diagrammatic and partly in cross-section, taken along the line 1—1 of Fig. 2 showing an apparatus embodying features of my invention;

Fig. 2 is a transverse view of a portion of the apparatus shown in Fig. 1;

Fig. 3 is a perspective of a portion of the wall structure shown in Figs. 1 and 2; and

Fig. 4 is a diagrammatic view showing a slightly modified form of control for the refrigerant liquefying unit.

An apparatus embodying features of my invention includes in general an air cooler past which air to be conditioned flows. The arrangement is such that there can be a thermal exchange provided between the air flowing to the air cooler and the air flowing away from the cooler, so that the conditioning of the air may include dehumidification with or without a substantial lowering of the dry bulb temperature. This is accomplished because the air flowing to the air cooler may have a portion of its sensible heat removed by the air leaving the cooler so that the air after being conditioned may be substantially at the same dry bulb temperature as it was before being conditioned, but a portion of its moisture content is removed by condensation on the cooler.

In the embodiment shown in the drawing, this is accomplished by providing an air cooler or evaporator 10 past which air is caused to flow by means of the fan 11 driven by the motor 12. Air going to and leaving the cooler 10 is caused to flow through a heat exchange structure 13, so that the air entering the conditioner at 14 gives up heat to the air leaving the conditioner at 15.

Means are provided for by-passing the heat interchanger to vary the action of the conditioner. This may be accomplished by providing a by-pass 16 so that the air entering the conditioner need not pass through the heat interchanger 13. The dampers 17 and 18 may be moved so that all of the air entering the condi-

tioner may pass through the by-pass 16 or only a portion of the air entering the conditioner may pass through the by-pass and the remainder may pass through the interchanger. This is accomplished by moving the dampers 17 and 18 to any of the many intermediate positions possible.

The heat exchanger 13 may be of any suitable construction which permits heat exchange between incoming and outgoing air; but as shown in Fig. 3, may include one or more walls 19 so arranged that air flowing to the cooler flows along one side of the wall and air leaving the cooler flows along the other side of the wall. This is accomplished by placing a corrugated metal sheet 20 on one side of a wall 19 with its corrugations so arranged that the air flows vertically therethrough. Another metal sheet 21 is placed on the other side of the wall with its corrugations so arranged that the air flows horizontally therethrough. The air-flow passages to and from the cooler are connected with the passages of the interchanger so that the air flowing to the cooler flows, for example, between the corrugations of the wall 21 while the air leaving the cooler flows, for example, through the corrugations of the wall 20. This is accomplished by providing central walls 22 on which the cooler 10 is supported and so that the passageway 23 between the walls 22 and the space 29 are connected to the spaces of the corrugated walls 21 while the spaces 24 on the outside of the walls 22 are connected to the spaces of the corrugated walls 20. The air conditioner which may have an outer casing 25 and may be placed in a space 26 the air for which is to be conditioned. Air to be conditioned may flow from the space 26 or from outside the space 26 or both, through the inlet 14, through the interchanger 13 past the cooler 10 and then up through the exchanger 15.

Means may be provided for by-passing one of the air streams around the interchanger 13 in accordance with air conditions. Thus a psychrometer 27 is adapted to actuate a lever 28 so that when the relative humidity increases the dampers are in the position shown in Fig. 1, but as the relative humidity decreases, the dampers 17 and 18 move towards the left, opening more and more the by-pass 16 and closing more and more the passageway between the space 29 and the passageway 23.

The psychrometer 27 may be of any suitable construction which is responsive to relative humidity or similar condition of the air. Thus it may include the wet bulb 30 and the dry bulb 31 arranged in opposed relationship and con-

nected to the arm 28 by the rod 32. When the relative humidity is high the position is as shown in Fig. 1, but as the relative humidity decreases the pressure within the dry bulb 31 becomes greater than that within the wet bulb 30 and thus the rod 32 is moved downwardly to tend to open the dampers 17 and closes the dampers 18. A compression spring 33 may be connected to the lever 28 and may be provided with an adjustment 34 in the form of a screw and knob so that the relative humidity to which the apparatus is responsive may be varied to suit individual needs.

The cooling action of the cooler or evaporator 10 may be varied in accordance with air conditions. Thus the operation of a refrigerant liquefying unit 35 may be made responsive to conditions within the space 26. The unit 35 may include a compressor 36, condenser 37, receiver 38 in refrigerant flow relationship with the evaporator 10. Liquid refrigerant flows through the line 39 to the evaporator 10 through the automatic expansion valve 40 and the evaporated refrigerant returns through the line 41 to the compressor 36. The valve 40 is of the type which automatically introduces liquid into the evaporator when the pressure therein is lowered below a predetermined limit. This valve may be provided with a thermostatic bulb 42 which automatically throttles the valve when the refrigerating effect at the outlet of the evaporator reaches a predetermined limit. The setting of the valve 40 is preferably such that temperature of the air cooling surfaces is maintained above the freezing point of water but sufficiently cool to provide the desired cooling effect on the air. The moisture removed by the evaporator falls into the pan 10a, which may connect with a suitable drain, not shown. A motor 43 drives the compressor 36 and is started and stopped by the switches 44 and 45, which are in electrical parallel relationship, and which are operated respectively by the wet bulb 46 and dry bulb 47 placed in the space 26. When either the dry bulb or wet bulb temperature in the space 26 rises above predetermined limits, motor 43 starts and when both the dry bulb and wet bulb temperature fall below predetermined limits respectively the motor 43 stops.

The operation of the refrigerant liquefying unit 35 may be made responsive to effective temperatures in lieu of the control shown in Fig. 1. Thus a switch 50 may control the starting and stopping of the motor 43 instead of the switches 44 and 45. The switch 50 may include a bi-metal thermostat 51 mounted on a fulcrumed platform 52 which is actuated by the arm 53 under the impulse of a member 54 which is responsive to relative humidity. These parts are so calibrated with respect to each other that the action of the thermostat 51 is modulated by the relative humidity to such an extent that the switch 50 is in effect responsive to the "effective temperature" rather than the dry bulb temperature. A hand adjustment 56, in the form of a screw-thread which 65 raises and lowers the member 54 is provided. The member 54 conveniently may be a piece of wood which is responsive to relative humidity.

While the form of embodiment of the present invention as herein disclosed, constitutes a preferred form, it is to be understood that other forms might be adopted, all coming within the scope of the claims which follow.

What is claimed is as follows:

1. Air conditioning apparatus comprising an evaporator, a refrigerant liquefying unit in re-

frigerant flow relationship to said evaporator, a motor driven fan causing the flow of air in thermal contact with said evaporator, a heat transfer wall, means causing an air stream flowing into thermal contact with said evaporator to flow past one side of said wall, means causing an air stream flowing after thermal contact with said evaporator to flow past the other side of said wall and into a space to be conditioned, means controlling the operation of said refrigerant liquefying unit in accordance with psychrometric conditions of the air in said space, and means for bypassing one of said air streams past said wall.

2. Air conditioning apparatus comprising an evaporator, a refrigerant liquefying unit in refrigerant flow relationship to said evaporator, a motor driven fan causing the flow of air in thermal contact with said evaporator, a heat transfer wall, means causing an air stream flowing into thermal contact with said evaporator to flow past one side of said wall, means causing an air stream flowing after thermal contact with said evaporator to flow past the other side of said wall and into a space to be conditioned, means controlling the operation of said refrigerant liquefying unit in accordance with psychrometric air conditions in said space, and means for bypassing one of said air streams past said wall in accordance with psychrometric air conditions.

3. Air conditioning apparatus comprising an evaporator, a refrigerant liquefying unit in refrigerant flow relationship to said evaporator, a motor driven fan causing the flow of air in thermal contact with said evaporator, a heat transfer wall, means causing an air stream flowing into thermal contact with said evaporator to flow past one side of said wall, means causing an air stream flowing after thermal contact with said evaporator to flow past the other side of said wall and into a space to be conditioned, means controlling the operation of said refrigerant liquefying unit in accordance with psychrometric air conditions in said space, and means for bypassing one of said air streams past said wall in accordance with relative humidity conditions of air in said space.

4. Air conditioning apparatus comprising a vertically disposed cabinet, a wall structure inside said cabinet dividing it into down flow and up flow air passages, air cooling means in said cabinet, and air heat exchange means in the upper part of said cabinet causing incoming air to flow in a direction transverse to discharged air and causing said discharged air to flow upwardly.

5. Air conditioning apparatus comprising a vertically disposed cabinet, a wall structure inside said cabinet dividing it into down flow and up flow air passages, air cooling means in said cabinet, heat exchange means in the upper part of said cabinet between incoming discharged air, and a separate air inlet into said cabinet below said heat exchange means.

6. Air conditioning apparatus comprising a vertically disposed cabinet, a wall structure inside said cabinet dividing it into down flow and up flow air passages, air cooling means in said cabinet, heat exchange means in the upper part of said cabinet between incoming discharged air, a separate air inlet into said cabinet below said heat exchange means, and means automatically controlling the flow of air through said inlet in accordance with psychrometric air conditions.

7. Air conditioning apparatus comprising a vertically disposed cabinet, a wall structure in-

- 5 side said cabinet dividing it into down flow and up flow air passages, air cooling means in said cabinet, heat exchange means in the upper part of said cabinet between incoming discharged air, an air inlet into said cabinet below said heat exchange means, and means automatically controlling the flow of air through said inlet in accordance with a function of the psychrometric conditions of air.
- 10 8. Air conditioning apparatus comprising a vertically disposed cabinet, a wall structure inside said cabinet dividing it into down flow and up flow air passages, air cooling means in said cabinet, and a corrugated metal structure in the upper part of said cabinet forming vertical and horizontal air passageways for incoming and discharged air.
- 15 9. An air conditioning apparatus comprising an air flow casing, a wall structure in said casing forming conditioned and unconditioned air passageways in said casing, a refrigerant evaporator in said casing for conditioning air, and an air heat exchanger connected to said air passageways and including a heat exchanger formed of a plurality of closely related corrugated metal sheets with transversely disposed corrugations forming transversely disposed air flow passageways within said corrugations.
- 20 10. An air conditioning apparatus comprising an air flow casing, a wall structure in said casing forming conditioned and unconditioned air passageways in said casing, a refrigerant evaporator in said casing for conditioning air, an air heat exchanger connected to said air passageways and including a heat exchanger formed of a plurality of closely related corrugated metal sheets with transversely disposed corrugations forming transversely disposed air flow passageways within said corrugations, and a refrigerant liquefying unit connected to said evaporator.
- 25 11. An air conditioning apparatus comprising an air flow casing, a wall structure in said casing forming conditioned and unconditioned air passageways in said casing, a refrigerant evaporator in said casing for conditioning air, an air heat exchanger connected to said air passageways and including a heat exchanger formed of a plurality of closely related corrugated metal sheets with transversely disposed corrugations forming transversely disposed air flow passageways within said corrugations, and a by-pass air inlet for by-passing incoming air past said heat exchanger, and means responsive to air conditions automatically controlling the flow of psychrometric air through said by-pass air inlet.
- 30 12. An air conditioning apparatus comprising an air flow casing, a wall structure in said casing forming conditioned and unconditioned air passageways in said casing, a refrigerant evaporator in said casing for conditioning air, an air heat exchanger connected to said air passageways and including a heat exchanger formed of a plurality of closely related corrugated metal sheets with transversely disposed corrugations forming transversely disposed air flow passageways within said corrugations, and means responsive to effective temperature controlling said air modifying means.
- 35 13. An air conditioning apparatus comprising an air flow casing, a wall structure in said casing forming conditioned and unconditioned air passageways in said casing, a refrigerant evaporator in said casing for conditioning air, an air heat exchanger connected to said air passageways and including a heat exchanger formed of a plurality of closely related corrugated metal sheets with transversely disposed corrugations forming transversely disposed air flow passageways within said corrugations, a by-pass air inlet for by-passing incoming air past said heat exchanger, and means responsive to psychrometric air conditions automatically controlling the flow of air through said by-pass air inlet.
- 40 14. An air conditioning apparatus comprising an air flow casing, a wall structure in said casing forming conditioned and unconditioned air passageways in said casing, a refrigerant evaporator in said casing for conditioning air, an air heat exchanger connected to said air passageways and including a heat exchanger formed of a plurality of closely related corrugated metal sheets with transversely disposed corrugations forming transversely disposed air flow passageways within said corrugations, a refrigerant liquefying unit connected to said evaporator, and means automatically controlling the operation of said refrigerant liquefying unit in accordance with psychrometric air conditions.
- 45 15. Air conditioning apparatus comprising a vertically disposed cabinet, a wall structure inside said cabinet dividing it into down flow and up flow air passages, air modifying means in said cabinet, a corrugated metal structure in the upper part of said cabinet forming vertical and horizontal air passageways for incoming and discharged air, and means responsive to effective temperature controlling said air modifying means.

CHARLES F. KETTERING.
